(57) **CLAIM**

The ornamental design for a clip for a semiconductor chip tray, as shown and described.

DESCRIPTION

FIG. 1 is a front perspective view of the clip for a semiconductor chip tray;

FIG. 2 is a front elevated view of the clip for a semiconductor chip tray shown in FIG. 1;

FIG. 3 is a rear elevated view of the clip for a semiconductor chip tray shown in FIG. 1;

FIG. 4 is a right side view of the clip for a semiconductor chip tray shown in FIG. 1;

FIG. 5 is a left side view of the clip for a semiconductor chip tray shown in FIG. 1;

FIG. 6 is a top view of the clip for a semiconductor chip tray shown in FIG. 1; and,

FIG. 7 is a bottom view of the clip for a semiconductor chip tray shown in FIG. 1.

The broken lines showing of a clip for a semiconductor chip tray which form no part of the claimed design.
